P. W. SEILER

WINDOW REGULATOR

Filed Oct. 14, 1922

Fig. 3

By

Stuart C. Barnes

Attorney

UNITED STATES PATENT OFFICE.

PAUL W. SEILER, OF DETROIT, MICHIGAN, ASSIGNOR TO TERNSTEDT MANUFACTURING COMPANY, OF DETROIT, MICHIGAN, A CORPORATION OF MICHIGAN.

WINDOW REGULATOR.

Application filed October 14, 1922. Serial No. 594,534.

To all whom it may concern:

Be it known that I, PAUL W. SEILER, citizen of the United States, residing at Detroit, in the county of Wayne and State of Michigan, have invented certain new and useful Improvements in Window Regulators, of which the following is a specification.

This invention relates to window regulators and has for its object a window regulator provided with a peculiar assembly for the counter-balancing spring and special provision to prevent the rattling of the counter-balancing spring. This difficulty due to vibration was recognized and provided for in the prior Allmand and Lawrence Patent 1,278,554 where a cupped gear and spring cup housed the counter-balancing spring.

It is the object of the present invention to eliminate the necessity of a spring cup and to provide a spring stress which will hold the counter-balancing spring and prevent vibration and objectionable rattling or chattering.

In the drawings:

Fig. 1 is an elevation of the top portion of a window regulator.

Fig. 2 is a section taken on the line 2—2 of Fig. 1.

Fig. 3 is a section taken on the line 3—3 of Fig. 2.

The regulator here shown happens to be a chain one in which a chain *a* runs over a sprocket wheel *b*. This is connected with a driven gear wheel *c* by means of a bolt *d*. A bushing *e* is secured on to the end of the bolt by the nut *f*. This bushing *e* rotates in the bearing *g* pressed from the cover plate. The driven gear *c* is simply a stamping with a plurality of circularly arranged lugs *h* punched out of the web of the gear wheel to form a spring casing. This is all that is necessary to hold the spring on the outside to prevent the same from moving outwardly.

However, the spring is still free to move sidewise, hence I provide one or more large flexible spring metal washers *j*. These are bowed and are bowed preferably only in such a way that they are really segments of a hollow cylinder rather than segments of a sphere. This is shown by the shading in Fig. 3, hence they will yieldingly contact every whorl of the spiral spring, yieldingly

hold the same in place and preventing the same from chattering with the vibration of the vehicle. This wholly eliminates any chattering or singing of the spring when the car is running over a rough road and aids in securing an absolutely noiseless closed body construction. The inside of these regulators, that is the internal of the cover plate, is packed with grease so that there is no objectionable friction or noise by rubbing.

It will be apparent that this is of even cheaper construction than the spring cup shown and claimed in the above referred to Allmand and Lawrence patent.

What I claim is:

1. In a window regulator, the combination of a gear, a casing in which the same is rotatably supported, a spiral counter-balancing spring contained in the casing adjacent to the gear and one or more spring metal washers bearing against the spiral spring to prevent vibration.

2. In a window regulator, the combination of a casing, a gear rotatably supported in the casing, a spiral counter-balancing spring supported in the casing adjacent to the gear and one or more spring metal washers bearing against the spring to prevent vibration, each washer in the form of a circular segment of a hollow cylinder.

3. In a window regulator, the combination of a casing, a gear rotatably supported in the casing and provided with punched-out lugs, a spiral counter-balancing spring contained within the punched out lugs of the gear and one or more bowed spring metal washers bearing between the casing and the counter-balancing spring.

4. In a window regulator, the combination of a casing, a gear rotatably supported in the casing and provided with annularly arranged punched out lugs, a spiral spring combined within the lugs and one or more bowed spring metal washers bearing between the casing and against the spiral spring each washer being formed as a segment of a hollow cylinder.

In testimony whereof I affix my signature.

PAUL W. SEILER.
